[57] CLAIM

The ornamental design for a frame for a clock or picture, as shown and described.

DESCRIPTION

FIG. 1 is a perspective view of a frame for a clock or picture, showing my new design;

FIG. 2 is a front elevational view;

FIG. 3 is a side elevational view, the opposite side being a mirror image thereof;

FIG. 4 is a top plan view; and,

FIG. 5 is a bottom plan view thereof.

The broken lines are for environmental purposes only and form no part of the claimed design.
